SOUND RECORDING

Burton F. Miller, Hollywood, Calif., assignor to
 United Research Corporation, Long Island
 City, N. Y., a corporation of Delaware

Application July 5, 1935, Serial No. 29,930

8 Claims. (Cl. 179—100.3)

My invention relates to sound recording and more particularly to sound recording systems and apparatuses employing means to reduce ground noise.

5 In my co-pending application #1, Ser. No. 28,109, filed June 24, 1935, I have disclosed and claimed an invention in which an anti-ground noise type of variable area sound track was produced by a single speech carrying conductor moving across a light aperture to change the length of the exposed portions of the aperture in accordance with the amplitude and frequency of the sound. Ground noise reduction was obtained by biasing a sufficient amount of current 10 through the conductor so as to keep the exposed portion of the sound track as small as possible. While the above application contains claims generic to the arrangement disclosed in detail herein, that case specifically discloses the 15 use of a triangular aperture in the path of the recording beam, the single conductor moving parallel to the base of the triangular aperture.

Also in my co-pending application #3, Ser. No. 29,931, filed July 5, 1935, I have disclosed and 20 claimed an invention in which an anti-ground noise type of variable area sound track was produced by a speech current carrying conductor moving across a rectilinear slit in accordance with sound waves. Ground noise reduction was obtained by biasing a sufficient amount of current 25 through the conductor so as to hold the zero line of modulation of the conductor as close to the exposed edge of the slit as possible. Although that case also contains claims generic to 30 the herein described arrangements it specifically discloses a single conductor for both recording sound and obtaining noise reduction.

In my present invention I disclose a similar 35 type of light valve employing a new and different type of noise reduction. As is well known, ground noise is produced largely by dust, oil, and dirt adhering to the clear portion of the sound track. These particles modulate the light received by the photo-cell of the sound reproducing system 40 and thus produce the ground tone or noise. The texture of the film and the grain of the emulsion also contribute to the generation of ground noise.

50 Although ground noise is of practically the same intensity throughout the length of the film, it is naturally much more noticeable during periods when sounds of a low level or no sound at all is reproduced.

55 Due to the shrinkage of the film or inaccuracies in the reproducing machine, the film has a

tendency to weave sideways as it passes the sound translating point. This weave is at times sufficient to allow one end of the light slit to cut off some of the sound track and thus clip the ends of the wave peaks. Although the peaks of the high level sounds may be cut a substantial amount without any apparent distortion of the reproduced sound, this is not true of the low level peaks.

5 It is therefore one object of my invention to keep the center of modulation of the speech current carrying conductor always at the center of the sound track.

Another object is to reduce the amount of clear 10 portion without biasing the speech current carrying conductor.

This is accomplished by providing two vibratory conductors, one carrying the speech currents and the other carrying the biasing current which is regulated in accordance with the envelope of the sound waves being recorded. The speech current carrying conductor is adjusted so that its center of modulation is approximately 15 in the center of the sound track. By keeping the center of modulation always in the center of the sound track, there will be no chance of clipping 20 the low level peaks.

Another object is to prevent clashing of the 25 two conductors.

This is accomplished by staggering the two 30 conductors, one slightly above the other, so that, as in the case of an instantaneously recorded high level sound, one conductor will be able to 35 pass beneath the other without clashing. The speech current carrying conductor is placed between the plane of the biasing conductor and the slit forming members to allow for sharper focusing. That is, it is necessary to sharply focus 40 the light from the exciter lamp onto both the edge of the speech conductor and the edge of the slit forming members so as to impress upon the moving film a series of sound wave representations with as sharp an edge as possible to define the opaque and transparent portions. Due to the 45 fact that the focus of the objective lens is usually very critical it is important that the speech conductor be placed as near to the slit forming members as possible. The biasing conductor does not require such critical focusing since the 50 edge produced thereby is not used to represent the sound waves.

More particularly referring to the drawing, Fig. 1 is an enlarged fragmentary view of a section 55 of moving picture film having a variable area

sound track recorded thereon in accordance with my improved light valve.

Fig. 2 is a schematic view showing the circuit for operating the light valve.

Fig. 3 is a transverse sectional view taken along the lines 3-3 of Fig. 4 of an improved type of light valve for recording variable area sound track.

Fig. 4 is a sectional view taken along the line 10 4-4 of Fig. 3.

Fig. 5 is an enlarged fragmentary view showing the light slit and its accompanying vibratory conductors.

Referring to Figs. 3 and 4, the valve generally indicated at 1 comprises a magnetic frame 2. The frame 2 is composed of a lower base plate 3 and an upper magnetic frame having a hollow core 5 in a central portion thereof. The core 5 forms one of the poles and is provided with a magnetizing coil 6 which is supplied with current of as constant an intensity as possible. A pole piece 7 is secured to the base plate 3 as by screws 7' and has an aperture 8 therein communicating with a second aperture 9 in a base plate 3, both of which are substantially in alignment with the hollow core 5. Slit forming members 10 and 11 are secured to the upper surfaces of the pole piece 7 by means of clamping pieces 12 and 13 thus leaving a slit, or aperture 17 between their adjacent edges. Screws 14 hold the clamping pieces 12 and 13 in position. End pieces 15 and 16 (Figs. 4 and 5) are provided to define the end of the slit 17 formed by the two pieces 10 and 11. This slit 17 has a relatively small width in comparison to its length, being in the order of .5 mil wide and about 140 mils long, although these dimensions may be varied to suit various conditions. A pair of insulated bridges 18 and 19 is provided on either side of the pole piece 7 and carries a pair of conductors 20 and 21. Each of the bridges 18 and 19 is provided with a pair of adjusting jaws 22 and 23. These jaws are preferably of a spring material and are secured at their rear edges to the bridges 18 and 19 by means of screws 24 and 25. The forward ends of the jaws 22 and 23 are engaged by suitable adjusting screws 26 and 27. Adjustment of these screws 26 and 27 causes sidewise movement of the conductors 20 and 21. The ends of the conductors 20 and 21 are secured upon rotatable windlasses 28, 29, 30 and 31. Each of the windlasses 28 to 31, inclusive, is carried by insulated blocks 50 secured to the base plate 3 as by screws 51. A slotted head 52 on each of the windlasses allows for adjustment to regulate the tension of the conductors 20 and 21. Conductors 53, 54, 55, and 56 provide electrical connection between the windlasses 28 to 31, inclusive, and terminals 57, 58, 59, and 60, respectively. At one end of each of the conductors 20 and 21, an insulated spring pressed arm 32 is provided, which is pivotally mounted at 61 and urged outward by a spring 62. This is secured within a loop formed by each of the conductors 20 and 21 to prevent undue tension from being applied to either of the conductors. Experience has indicated that an angle of about one degree is satisfactory to produce a full modulation of the light beam. From now on I shall term one of the conductors 20 as the envelope following conductor. When either low level or no sound is being recorded, the conductor 20 lies normally in a position shown by the full lines in Fig. 5. At high level modulation of the conductor 21, the conductor 20 lies in a position shown by the dotted lines 33 so as to allow maxi-

mum excursions without interference of the speech current carrying conductor 21.

Referring now to Fig. 2 which is a schematic diagram of the circuit employed for operating the light valve, a microphone 34 is provided to receive the sounds desired to be recorded upon the sensitized surface of a moving film 35. Speech currents produced in the microphone 34 are amplified by means of a suitable amplifier 36 and are passed through transformer 37 from whence they are fed to the conductor 21 through lines 38 and 39. The modulated voice currents which are passed through the conductor 21 set up a magnetic field produced by the pole pieces 5 and 7 and thus cause movement of the conductor 21 so as to uncover a greater or a less length of the slit 17. Light from the exciter lamp 40 is projected through a condenser lens 41 and is focused preferably upon the conductor 21 and the slit 17 from whence it is projected onto the film 35 by means of an objective lens 42, which reduces the image of the slit about half size.

I will now describe the means for moving the conductor 20 in accordance with the amplitude of the sounds being recorded. A biasing current of constant potential is fed by a battery 47 to the terminals of the conductor 20 by means of lines 45 and 46 to hold it in a position shown by the full lines 20 of Fig. 5, when no or little sound is being recorded. An amplifier 43 and rectifier 44 are shunted across the terminals of the transformer 37 and current passing therethrough is conducted by the lines 45 and 46 to the conductor 20 in a direction opposing the steady current passed by the battery 47. When low level sounds are being recorded, only a small amount of rectified current is passed through the rectifier 44 but when high level sounds are recorded, a correspondingly greater amount of rectified current is passed through the conductor 20 in opposition to the biasing current from the battery 47. This action neutralizes the biasing effect of the conductor 20 and allows it to take a position shown by the dotted lines 33 (Fig. 5). It is to be understood of course that the shifting of the center of modulations is proportional to the amplitude of the sound so as to allow the edge 63 of the blocking portion 64 (Fig. 1) to closely follow the peaks of the wave forms 66 which represent the sound modulations.

The biasing of the conductor 20 may also be obtained by applying the rectified current from the rectifier 44, which varies in accordance with the amplitude of the sounds being recorded, directly to the conductor 20. In this case, the battery 47 would be omitted and the normal position of the conductor 20 would be mechanically adjusted so that at low level modulation, it would take the position shown by the full lines 20 (Fig. 5). With the increase in amplitude of the sound being recorded, the corresponding increase in rectified current would shift the center of modulation of the conductor 20 to the dot and dash lines 32.

Referring now to Fig. 3, it will be noted that the conductors 20 and 21 are staggered one above the other so as to prevent clashing. This is especially advantageous when recording of staccato sounds in which the increase in amplitude is practically instantaneous. In such a case, the conductor 21 may not have a chance due to the electric or magnetic lag to be moved out of the way soon enough to allow the conductor 21 to move to its maximum position.

It should also be noted that the speech conductor 21 is in a position next to the members 10 and 11 defining the slit 17 to allow the beam of light from the exciter lamp 40 (Fig. 2) to be sharply focused at a point between the plane of the conductor 21 and the plane of the members 10 and 11. In practice, this will produce a sharp edge to both the shadow of the conductor 21 and the shadow of the slit forming members 10 and 11. In the case of a critically focused beam of light, the distance between the plane of the envelope following conductor 20 and the plane of the members 10 and 11 may cause the edge of the shadow of the conductor 20 to be slightly hazy or fuzzy. In other words, the edge 63 of the blocking portion 64 on the sound track 65 (Fig. 1) may not be sharply defined but will be slightly fuzzy. Due to the fact that the portion 64 is used merely for blocking out the clear portions of the positive sound track and also due to the fact that the fuzziness, if any, will be very small, it will be seen that it will not affect the quality of the sound or the amount of ground noise.

Having thus described the invention, what is claimed as new and desired to secure by Letters Patent, is:

1. A sound recording system for variable area type sound records comprising a rectangular aperture forming member, a vibratile electrical conductor cooperating therewith, means for vibrating said conductor in accordance with sound waves, a second vibratile conductor cooperating with said aperture, and means for moving said second conductor in accordance with the envelope of said sound waves, each of said conductors individually cooperating with said aperture to form separate light traces.

2. A system for recording an anti-ground noise type of sound record comprising means forming a rectilinear slit member, a vibratile electrical conductor angularly disposed across said slit, means for moving said conductor in accordance with sound waves, a second vibratile conductor angularly disposed across said slit, and means for moving said second conductor in accordance with the envelope of said sound waves, each of said conductors individually cooperating with said slit to form separate light traces.

3. A sound recording system for anti-ground noise type of variable area records comprising an opaque member having a rectilinear slit therein, a pair of separate vibratile electrical conductors cooperating with said slit, one of said conductors being disposed in a plane between the plane of the other conductor and said opaque member, means for moving one of said conductors in accordance with sound waves being recorded, means for moving the other of said conductors in accordance with the envelope of said sound waves, and means for directing a beam of light through the opening formed by said slit and said conductor.

4. A system for recording an anti-ground noise type of variable area sound record comprising, a member having a rectilinear slit therein, a vibratile current carrying conductor disposed at an acute angle across said slit and adjacent thereto, means for vibrating said conductor in accordance with sound waves, a second vibratile current carrying conductor disposed at an acute angle across said slit and in a plane above that of said first mentioned conductor, means for moving said second conductor in accordance with the

envelope of said sound waves, and means for directing a beam of light through the opening formed by said slit and said conductors.

5. A sound recording system comprising a source of light, means for supporting a light sensitive material, means for projecting light from said source on said material, means for generating electrical currents corresponding to sound waves, a light valve interposed between said light source and light sensitive material, means for impressing said electrical currents on said valve, said valve comprising a pair of vibratile conductors, one of which vibrates in accordance with the sound waves and the other of which vibrates in accordance with the envelope of said sound waves, a rectangular slit forming member cooperating with said conductors, said conductors being mounted at an angle across said slit, and means for adjusting each of said conductors individually with respect to said slit. 20

6. A system for recording sound waves which comprises a light source, photographic film, means for transmitting light from said source to said photographic film, means for varying the amount of transmitted light comprising a member having an elongated slit therein, a pair of electrical conductors arranged in a magnetic field and adjacent the slit in said member to define a light transmitting slot, means for supplying electrical currents to one of said conductors to effect 30 a variation in the space relation between said conductor and said other conductor in accordance with the instantaneous values of said currents, and means for supplying electrical currents to the other of said conductors to effect a 35 variation in its space relation with respect to the other of said conductors in accordance with the envelope of said electrical currents, said conductors and said slit member being disposed in oblique relation to each other. 40

7. In combination, a light source, a photographic film, means for varying the amount of transmitted light from said source to said film, said means comprising a member having a fixed, elongated aperture therein and a pair of movable 45 elements suspended in a magnetic field and disposed in oblique relation to the aperture in said member, means to supply modulated electrical currents to said movable element to effect a movement of one of said conductors with respect 50 to the other of said conductors in accordance with the instantaneous values of said currents and means to supply currents to the other of said movable elements to effect movement thereof with respect to the first mentioned electrical element 55 in accordance with the envelope of said modulated electrical currents.

8. The method of producing a variable area-variable density sound track having noise reduction with a light valve having a pair of electrical 60 conductors disposed in oblique relationship to a fixed rectangular slit comprising vibrating one of said conductors with modulated electrical currents and vibrating the other of said conductors in accordance with the envelope of said currents, 65 said first conductor being adapted to vibrate over the entire rectangular aperture at high amplitude currents and over the mid portion of said rectangular slit for low amplitude currents, while said second conductor uncovers said slit at high 70 amplitude currents and covers said slit in proportion to the amplitude of the envelope currents.
